UNITED STATES PATENT OFFICE.

PATRICK O'CONNOR, OF TALLMAN, MICHIGAN.

SHINGLE-SAWING MACHINE.

SPECIFICATION forming part of Letters Patent No. 292,347, dated January 22, 1884.

Application filed July 19, 1883. (No model.)

To all whom it may concern:

Be it known that I, PATRICK O'CONNOR, of Tallman, in the county of Mason and State of Michigan, have invented certain new and useful Improvements in Rotary Shingle-Machines, of which the following is a full, clear, and exact description.

Reference is to be had to the accompanying drawings, forming part of this specification, in which similar letters of reference indicate corresponding parts in all the figures.

Figure 1, Sheet 1, is a plan view of my improvement, part being broken away. Fig. 2, Sheet 2, is a sectional side elevation of the same. Fig. 3, Sheet 3, is a sectional plan view of the same, taken through the broken line $x x x x$, Fig. 2. Fig. 4, Sheet 4, is a side elevation of the same, part being broken away. Fig. 5, Sheet 4, is a sectional elevation of one of the tables and its support. Fig. 6, Sheet 4, is a side elevation of one of the arm-holding pins. Fig. 7, Sheet 4, is a side elevation of one of the hinged bars, and showing a part of a narrow dog. Fig. 8, Sheet 4, is a sectional elevation of one of the dogs, and showing a part of the rotary frame.

The object of this invention is to facilitate the sawing of shingles and promote accuracy in such sawing.

The invention consists in a shingle-machine constructed with a stationary frame and a rotary annular frame divided into compartments by stationary and hinged bars, and provided with stationary dogs and with movable dogs operated by spring-pressed jointed bars and cam-guides, and tilting tables and their adjusting mechanism, and with a driving mechanism, as will be hereinafter fully described.

A is the base-frame of the machine, to which are attached the lower ends of a number of posts, B.

To the upper ends of the posts B is attached a horizontal frame, C.

In bearings in the center of the frame C revolves a vertical shaft, D, the lower end of which revolves in a step placed in a socket, E, and centered by set-screws F, passing in through the sides of the said socket and resting against the sides of the said step.

To the upper end of the shaft D is keyed or otherwise rigidly attached the center of an

arched frame or spider, G, to the ends of the radial arms of which is bolted an annular frame, H, formed of two concentric rings connected by bars dividing the space between the said rings into compartments, to receive the blocks from which the shingles are to be sawed. The bars of the annular frame H incline forward, as shown in Fig. 1, so as to carry the blocks squarely against the saws. Two or more of the compartments of the annular frame H are made large, and are provided with three bars, H', hinged at their inner ends to the inner rim of the said frame. The outer ends of the bars H' shut down into grooves in the inner side of the outer rim of the frame H. With this construction, by raising the central bar H', as shown at the right-hand side of Fig. 1, three compartments will be formed to receive three small shingle-blocks, and by raising the two side bars H', two compartments will be formed to receive larger shingle-blocks.

The shingles are cut from the lower sides of the blocks by the circular saws I, which are secured at their centers by three bolts, J, to the upper ends of the vertical shafts K. The upper parts of the shafts K revolve in bearings L, secured by set-screws M in recesses in the frame C, and their lower ends revolve in steps N, placed in sockets O, and secured in place by set-screws P, so that the shafts K can be readily centered. The saws I are both driven by the same belt Q, which passes around small pulleys R, attached to the shafts K, and around a large guide-pulley, S, attached to the shaft T, which revolves in bearings attached to the top and base frames, C A, and is placed midway between and at a little distance in front of the shafts K, so as to give the belt Q a sufficient bearing upon the pulley R S to prevent the said belt from slipping. The belt Q passes around guide-pulleys U, pivoted to brackets V, attached to the floor or other suitable support, and passes thence to and around a pulley, W, attached to a counter-shaft, X, which is driven by a belt, Y, and pulley Z, or other suitable means, from any convenient power. The drive-belt Q is thus driven by a shaft below the floor and in a horizontal position by the aid of idlers on the floor, the said belt making a quarter-twist to and from the machine.

To the shaft T, below the large pulley S, is attached a small pulley, a, around which passes a belt, b. The belt b also passes around a large pulley, c, attached to the shaft d, which revolves in bearings connected with the frames C A, and to which is attached a small gear-wheel, e. The teeth of the gear-wheel e mesh into the teeth of a large gear-wheel, f, attached to the central shaft, D, that carries the annular frame H, so that the said frame will be driven from the shaft T. The belt b is made taut by a roller, g, pivoted to an arm of the elbow-lever h, which is pivoted at its angle to a bracket, i, attached to the frame A or other support.

To the end of the outer arm of the elbow-lever h is attached the end of a cord, j, which passes around a pulley, k, pivoted to a post, B, or other suitable support. To the other end of the cord j is attached a weight, l, of such a gravity as to press the roller g against the belt b with force sufficient to give the requisite tautness to the belt b.

With the end of the outer arm of the elbow-lever h is connected the end of a rod, m, the other end of which is connected with the end of a short arm, n, formed upon or rigidly attached to the vertical shaft o. The shaft o is pivoted in bearings in the frames A C, and upon it is formed, or to it is rigidly attached a long arm, p, the shaft o and arms n p thus serving as a lever for withdrawing the tension-roller g from the belt b when it is desired to stop the movement of the annular frame H without stopping the saws.

To three or more of the posts B are attached U-shaped brackets q, the outer ends of which are perforated to receive the pins r.

Upon the pins r, between the arms of the brackets q, are placed spiral springs s, the lower ends of which rest upon the lower arms of the brackets q.

Upon the upper ends of the springs s rest collars t, formed upon or attached to the pins r, below the upper arms of the said brackets. The upper ends of the pins r are forked, and to them are pivoted small rollers u, which bear against the lower side of the rim of the annular frame H. By this construction the central shaft, D, will be relieved from a part of the weight of the annular frame H, and the said frame will be held in a horizontal position. With this construction, should sawdust or other substance get upon the surface of the rollers u the springs s will yield and thus prevent the circular frame H from being tilted and the shingles from being cut untrue.

The shingle-blocks while passing from one saw toward the other rest and slide upon the curved bars or rails v attached to the frame C, beneath the annular frame H, and extending from the rear side of each saw I, nearly to the forward side of the other saw. The shingle-blocks while passing from the rails v to the saws I rest and slide upon the top bars of the

tables w, which are curved to correspond with v and serve as a continuation of the rails v. The center of each table w is formed upon or rigidly attached to the upper end of a standard, x, the lower end of which rests upon the end of the short arm of an elbow-lever, y, so that the lower end of the said standard can be moved in and out radially to tilt the table w. The upper part of the standard x passes through an opening in a bar of the frame C and through a slot in a bearing-block, z, placed upon the said slotted bar of the frame C, the said slot being so formed as to allow the lower end of the standard x to be moved radially, and to serve as a fulcrum to the said standard in its movements. The bearing-block z is secured in place by set-screws 1, which pass in through screw-holes in lugs 2 attached to the bar of the frame C, so that the said block can be adjusted and trued by means of the said set-screw 1. The center bar of the table w is recessed in the center of its upper side to receive the arm 3, which passes through a hole in the forward bar of the said table w, and its projecting part is so formed that its upper surface will be flush with the upper surface of the table w. The arm 3 is designed to support the shingle-block as it is passing from the table to the saw, as the dogs hereinafter described do not grasp the said block till it is about coming in contact with the saw. The arm 3 is held from longitudinal movement in the table w by collars 29, attached to the said arm upon the opposite sides of the center bar of the said table w, and the said arm is held from turning when the table w is tilted by eye-pins 30, the eyes of which are made triangular to fit upon a triangular-shaped part of the said arm, and the shanks of which enter holes in the bearing-block z, as shown in Fig. 5. The eye-pins 30 move up and down in the holes in the bearing block z as the table w is raised and lowered and at the same time fit the said holes so accurately as to hold the table w steady. The lower end of the standard x is recessed to receive the end of the lever y, and the upper end of the said lever is recessed to receive the lower end of the said standard, so that the standard will be kept in place upon the lever. The bottom of the recess in the lower end of the standard x is straight, and the bottom of the recess in the upper end of the lever y is curved upon the arc of a circle having its center at the pivot of the said lever, so that the table w can be tilted without having its height varied. The movement of the lower end of the standard x is limited, and regulated by two set-screws, 4, one of which passes in through a screw-hole in the post B, and the other passes in through a screw-hole in an upright, 5, connected at its upper end with the said post B, and at its lower end with the base-frame A. The lever y is pivoted at its angle to the slotted head of a screw, 6, which screws into a foot, 7. The lower end of the

foot 7 is rounded, and rests in a recess in the base-frame A, or in a support attached to the said base-frame. The upper part of the foot 8 is squared, to adapt it to be grasped by a wrench, so that the height of the table can be regulated to give the desired thickness to the shingles by turning the said foot on and off the screw 6. The foot 7 is kept from turning upon the screw 6 by a jam-nut, 8, placed upon the said screw, and turned down against the said foot.

To the pin that pivots the lever y to the screw 6 is pivoted the forked end of a bar, 9, which passes through a guide-slot in the upright 5, and to its outer end is pivoted the slotted upper end of a screw-bolt, 10, the lower end of which is passed through an eye in the outer end of the bolt 11 where it is secured in place adjustably by nuts screwed upon it above and below the said bolt 11. The bolt 11 passes through the upright 5, and has nuts screwed upon it upon the opposite sides of the said upright 5. By this construction, by adjusting the bolts 10 11, in connection with the set-screws 4, the movement of the table w can be regulated to give any desired taper to the shingles.

As shown in the drawings, the table w next to the sawyer, which is the right-hand table in Fig. 2, is set to cause the butts of the shingle-blocks resting upon it, and the other, which is the left-hand table in Fig. 2, is shown as set to cut the butts of the shingles from the outer ends of the said shingle-blocks, as indicated by the heavy dotted lines in Fig. 2, the right-hand table being held in position by a weight, 12, suspended from the outer end of the lever y, and the left-hand table being held in position by a spring, hereinafter described.

With the outer part of the lower arm of the left-hand lever y is connected the upper arm of one of two elbow-levers, 13, which levers 13 are pivoted at their angles to the posts B or other suitable supports. The lower arms of the two levers 13 are connected by a rod, 14, so that the said two levers 13 will always move together.

With the outer arms of the elbow-levers y are connected the lower ends of the upright 15, which pass up through keepers attached to the posts B or frame C, and have small rollers 16 pivoted to the inner sides of their upper ends.

To the lower part of the rim of the annular frame H is attached, or upon it is formed, a flange, 17, which is made in as many parts or sections as there are ordinary-sized block-receiving spaces in the said annular frame H, and has openings between the adjacent ends of the said sections of sufficient width to allow the rollers 16 to pass through. The bar 15 at the right hand side of the machine, on the side at which the sawyer stands, is held down, so that its roller 16 will be below the flange 17 by the weight 12 connected with the lever y of

the said bar 15, and the other bar 15 is held up, so that its roller 16 will be above the flange 17, by a spring, 18, connected with the last-mentioned bar 15 and with the post B or frame C.

To supports 19 19', attached to the base-frame A or other suitable supports, are pivoted foot-levers 20 20', with their forward ends beneath the outer arms of the right-hand levers 75 y and 13, respectively, and their rear ends projecting into such positions that they can be conveniently reached and operated by the sawyer with his foot. With this construction, when the sawyer operates either of the foot-levers 20 20', the corresponding lever, y, will be operated to force the friction-roller 16 against the flange 17 until it reaches and passes through the opening between two sections of the said flange, allowing the said lever y to move the 85 standard x and tilt the table w, so that the next shingle will be cut with its butt in a reversed position. When the roller 16 comes to the next opening in the flange 17 it is made to pass through the said opening by the pressure of 90 the weight 12 or spring 18, and the machine continues its work as before. This construction enables the sawyer to true and grain the blocks or timber should the said blocks be cut down upon one end faster than upon the other. 95

To the lower side of the rim of the annular frame H, opposite each compartment of the said frame, is attached a stationary dog, 21, to engage with the outer end of the shingle-block, and in connection with the movable dog 22 100 hold the said block while being sawed. The dogs 22 slide in dovetailed grooves in the lower side of the inner rim of the annular frame H, or upon plates secured to the lower side of the said inner rim.

To the inner part of each dog 22 is hinged the outer end of a bar, 23, the inner end of which is hinged to a plate, 24, keyed or otherwise secured to the shaft D. The bars 23 have hinged joints in their centers, so that the dogs 22 can be drawn inward to release the shingle-blocks by raising the middle parts of the said jointed bars. This is done by the cam plates or bars 25, the lower edges of which are secured to the frame C. 115

The upper edges of the cam-plates 25 are so formed as to withdraw the dogs 22 as soon as the shingle-blocks have passed the saws, and allow the said blocks to drop upon and slide along the rail v, and to allow the said dogs to 120 be forced outward to hold the shingle-blocks as the said blocks are about to come in contact with the saws I.

The jointed middle parts of the bars 23 are forced downward to force the dogs 22 outward 125 by spiral or other springs, 26, interposed between the said bars and the circular plate 27, keyed or otherwise secured to the shaft D.

The spiral springs 26 are kept in place by guide-pins 28, attached to the bars 23, and 130 passing through the springs 26 and plate 27.

The hinge-joints of the bars 23 are so con-

structed as to prevent them from being clogged by sawdust.

The inner ends of the central hinged bars H' project so low as to rest against and hold back the small movable dogs 22, as the said small dogs are required to act only when the said central bars are raised.

The parts of the saws I that project beyond the rim of the annular frame H are covered by shields 31, the ends of which are attached to the frame C, or to supports attached to the said frame, to prevent persons and things from coming in contact with and being injured by the said saws.

15 I do not abandon or dedicate to the public any patentable feature set forth herein and not hereinafter claimed; but reserve the right to claim the same either in a reissue of any patent that may be granted upon this application, or in any other application for Letters Patent that I may make.

Having thus described my invention, I claim as new and desire to secure by Letters Patent—

1. In a rotary shingle-machine, the rotary frame H, formed of two annular rings connected by inclined bars dividing the same into block-compartments, substantially as herein shown and described, whereby provision is made for presenting the blocks squarely to 30 saws, as set forth.

2. In a rotary shingle-machine, the combination, with the rotary frame H, divided into compartments by inclined bars, of the hinged bars H', for subdividing said compartments, substantially as herein shown and described.

3. In a rotary shingle-machine, the combination, with the frame C, the shaft D, the block-holding frame H, provided with the stationary dogs 21, and attached to said shaft, 40 and means for operating the said shaft, of the jointed and spring-pressed bars 23, hinged to supports attached to the shaft, the dogs 22, on the free ends of the said bars, and the cam-plates 25, secured to the frame, substantially 45 as herein shown and described.

4. In a rotary shingle-machine, the combination, with the frame C, shaft D, the block-holding frame H, the hinged and jointed bars 23, carrying dogs 22 on their free ends, and 50 the cam-plates 25, of the plate 27, secured to the shaft D, the pins 28, secured to jointed bars and passing through apertures in the said plate, and the springs 26, surrounding the pins, substantially as herein shown and described.

5. In a rotary shingle-machine, the combination, with the frame C, the track v, and the rotary frame H, of the tables w, having their top bars curved to form a continuation of the track v, the standards x, to which the tables 60 are attached, and the elbow-levers y, pivoted to adjustable supports, substantially as herein shown and described.

6. In a rotary shingle-machine, the combination, with the frame C, the track v, and the 65 tilting tables w, having their top bars curved to form a continuation of the track, of the arms

3, projecting from the front parts of the tables, and having their upper surfaces flush with the tables, substantially as herein shown and described.

7. In a rotary shingle-machine, the combination, with the standard x, carrying a table at its upper ends, of the foot 7, resting on the base-frame, the screw 6, entering the foot and provided with the jam-nut 8, and the elbow-lever y, pivoted to the head of the said screw and supporting the standard x, substantially as herein shown and described.

8. In a rotary shingle-machine, the combination, with the upright 5, the screw 6, and 80 the elbow-lever y, pivoted to said screw and carrying a table-standard, of the bar 9, pivoted to the screw, the screw-bolt 10, pivoted to the outer end of the bar 9, and the eyebolt 11, connected to the screw-bolt 10 and adjustably secured to the upright 5, substantially as herein shown and described.

9. In a rotary shingle-machine, the combination, with the post B, the upright 5, the table-standard x, and the elbow-lever y, supporting said standard, of the set-screws 4, the bar 9, pivoted to the support of the said elbow-lever, the screw-bolt 10, pivoted to the end of the bar 9, and the eyebolt 11, adjustably secured to the upright 5, substantially as herein 95 shown and described.

10. In a rotary shingle-machine, the combination, with the standard x and the table w, having its central bar recessed, of the apertured adjustable bearing-block z, the arm 3, 100 provided with collars 29, and the eyebolts 30, projecting into the apertures of the bearing-blocks, substantially as herein shown and described.

11. In a rotary shingle-machine, the combination, with the standards x, carrying the tables w at their upper ends, and the elbow-lever y, in which the said standards are stepped, of the elbow-levers 13, connecting-rod 14, and treadle, substantially as herein shown and described.

12. In a rotary shingle-machine, the combination, with the block-carrying frame H, provided with the sectional flange 17, and the elbow-levers y, carrying the table-supporting standards x, of the bars 15, connected with the elbow-levers y, and provided with the rollers 16 at their upper ends, the weight 12, and spring 18, substantially as herein shown and described.

13. In a rotary shingle-machine, the combination, with the block-carrying frame H, provided with the sectional flange 17, and the elbow-levers y, carrying the table-supports x, of the bars 15, secured to the elbow-levers and carrying rollers 16 at their upper ends, the weight 12, spring 18, elbow-levers 13, and the treadles 20 20', substantially as herein shown and described.

14. In a rotary shingle-machine, the combination, with the saws I, means for operating them, and the block-holding frame H, oper-

ated from the saw-driving mechanism by the belt *b* and intermediate mechanism, of the elbow-lever *h*, provided with the roller *g*, the cord *j*, attached to the end of lever *h* and provided with the weight *l*, the connecting-rod *m*, and shaft *o*, provided with arms *n p*, substantially as herein shown and described, where-

by provision is made for stopping and starting the block-holding frame without affecting the movement of the saws, as set forth.
